US00D774498S

(12) **United States Design Patent** (10) **Patent No.:** **US D774,498 S**
(45) **Date of Patent:** **** Dec. 20, 2016**

(54) **COVER FOR ELECTRONIC COMMUNICATIONS DEVICE**

(71) Applicant: **BlackBerry Limited**, Waterloo (CA)

(72) Inventors: **Di Tao**, Toronto (CA); **Alison Phillips**, Toronto (CA); **Patrick Edward Everts Kroetsch**, Toronto (CA)

(73) Assignee: **BlackBerry Limited**, Waterloo, Ontario (CA)

(**) Term: **14 Years**

(21) Appl. No.: **29/512,062**

(22) Filed: **Dec. 16, 2014**

(51) **LOC (10) Cl.** **14-03**

(52) **U.S. Cl.**

USPC **D14/250**

(58) **Field of Classification Search**

USPC D14/238.1, 250, 440, 203.3–203.7, D14/217, 240, 248, 251–253, 447, 496, D14/143, 189, 203.2; D3/201, 218, 247, D3/269, 273, 301, 303; D13/103, D13/107–108, 119

(57) **CLAIM**

The ornamental design for a cover for electronic communications device, as shown and described.

DESCRIPTION

FIG. 1 is a perspective view of the cover for electronic communications device showing an interior thereof; FIG. 2 is another perspective view showing an exterior thereof;

FIG. 3 is an elevation view showing an interior thereof; FIG. 4 is another elevation view showing an exterior thereof;

FIG. 5 is a side elevation view thereof;

FIG. 6 is another side elevation view thereof;

FIG. 7 is a plan view thereof; and,

FIG. 8 is another plan view thereof.

The broken line in FIG. 8 depicts environmental subject matter that forms no part of the claimed design.

1 Claim, 6 Drawing Sheets
